UNITED STATES PATENT OFFICE.

SHIRLEY H. BOSSART, OF BIRMINGHAM, ALABAMA.

AIR-PUMP.

1,352,348.

Specification of Letters Patent. Patented Sept. 7, 1920.

Application filed November 13, 1918. Serial No. 262,326.

To all whom it may concern:

Be it known that I, SHIRLEY H. BOSSART, a citizen of the United States, residing at Birmingham, in the county of Jefferson and 5 State of Alabama, have invented new and useful Improvements in Air-Pumps, of which the following is a specification.

This invention has reference to tire pumps for automobiles and the principal object 10 of the invention relates to the novel construction of the pump and the means for securing the pump to the running board of the automobile.

The invention also consists in certain other 15 features of construction and in the combination and arrangement of the several parts, to be hereinafter fully described, illustrated in the accompanying drawings and specifically pointed out in the appended claim.

20 In describing my invention in detail, reference will be had to the accompanying drawings wherein like characters denote like or corresponding parts throughout the several views, and in which:—

25 Figure 1 is a part sectional view showing the pump in operative position on a running board of an automobile;

Fig. 2 is an end view;

Fig. 3 is a detail view of the plunger.

30 In these views, 1 indicates the running board of an automobile and 2 indicates the casing or box for containing the pump 3 when the same is not in use. The casing is formed of two portions 4 and 5, the lower 35 portion 4 being secured to the running board by any suitable means. The portion 5 is hinged to the portion 4 by the hinge 6 so that said portion 5 may be swung upwardly to permit the removal of the pump. As

40 shown, the two portions are formed by dividing the casing substantially diagonally. A base 7 is secured to the bottom of the casing and said base at one end is provided with a pair of ears 8. The other end of the 45 base is provided with a slotted enlargement 9.

The pump 3 consists of a pair of cylinders 10 secured to a base 11, and the usual pistons 12 and the rods 13. The base 11 is provided 50 with the ears 14 which are pivoted to the ears 8 so that the pump may be rocked into and out of the casing. A link 15 has one end pivoted to the upper part of the pump

and its other end having an offset portion which is adapted to engage the slot in the 55 enlargement 9 to hold the pump in upright position. The piston rods 3 are connected to a T-shaped member 16 by the links 17 and said member is pivoted to an upright 19 forming part of the pump. The member 16 60 has one arm provided with a socket 20 to receive the handle 21 of which the member may be rocked to reciprocate the pistons. 22 is a handle carried by the part 19 for facilitating the operation of the pump. I 65 prefer to form each piston of a leather cup 23 with a follower 24 above the same and a head 25 below the same, these parts being engaged by the screw threaded end of the 70 piston rods 13.

It will thus be seen that when the pump is not in use it is carried in an inclosed casing on the running board of the automobile. When the pump is to be used the upper part of the casing is swung upwardly 75 and the pump moved into upright position and held in this position by the link 15. Then by placing the handle 21 in the socket 20, and steadyng the pump by the handle 22 the pump may be operated to inflate the 80 tires. It will be understood that a sufficient length of hose must be connected with the outlet of the pump to reach to all four of the 85 wheels.

It is thought from the foregoing description that the advantages and novel features of my invention will be readily apparent.

I desire it to be understood that I may make changes in the construction and in the combination and arrangement of the several 90 parts, provided that such changes fall within the scope of the appended claim.

Having described the invention, what is claimed is:—

A device of the class described comprising 95 a casing, a pump hingedly secured thereto and comprising a pair of cylinders, pistons therein, rods connected with the pistons, an upright connected with the pump, a T-shaped member pivoted to said upright, 100 links connecting two arms of the T-member with the piston rods and the other arm having a socket therein and a handle for engaging said socket.

In testimony whereof I affix my signature. 105
SHIRLEY H. BOSSART.
